VALVE KEEPER REMOVER

Howard L. Crook, William H. George, and William H. Kleinsmith, Jackson, Miss.

Application May 16, 1938, Serial No. 208,286

1 Claim. (Cl. 29—86.3)

This invention relates to a valve keeper remover, the general object of the invention being to provide a device for depressing the springs of valves of a motor and holding the springs depressed while the keepers are being removed, so that the valve assemblies can be removed for grinding and other purposes, the invention also being used in replacing the valves by holding the springs depressed while the keepers are being put in place.

The invention also consists in certain other features of construction, combination and arrangement of the several parts, to be hereinafter fully described, illustrated in the accompanying drawing and specifically pointed out in the appended claim.

In describing the invention in detail reference will be had to the accompanying drawing wherein like characters denote like or corresponding parts throughout the several views, and in which:

Fig. 1 is a fragmentary sectional view through a part of a motor showing the invention as used in holding the valves depressed, the keepers having been removed.

Fig. 2 is a top plan view of Fig. 1.

Fig. 3 is a sectional view of the valve keeper remover.

Fig. 4 is a perspective view looking towards the under side of the device.

Fig. 5 is a detail view showing the keepers in place on a valve stem, the keepers being shown in section.

As shown in this drawing, the device is composed of a plate-like member 1 having a pair of holes 2 therein which are spaced apart a sufficient distance to receive a pair of valve stems 3 of the valve arrangement of a motor. A circular recess 4 surrounds each hole on the bottom of the member for receiving the upper spring seat 5. A recess 6 surrounds each hole on the upper face of the member, thus recess curving downwardly from the top face of the member to the hole as shown. These recesses 6 enables the keepers 7 to be readily removed from the annular groove 8 in the upper end of each stem, it being understood that the reduced part formed by the groove, tapers downwardly and that the keepers are similarly formed and that the keepers act to hold the spring seat in place at the upper end of the stem.

A tubular part 9 extends downwardly from the member 1 in rear of the holes and in a plane passing between the holes and a hole 10 passes through the member and registers with the bore

of the tubular member so that a head bolt 11 of the motor can pass through. Thus the member or part 9 spaces the device from the motor head and by tightening the nut 12 of the bolt the member 1 will be caused to compress the springs 13, as shown in Fig. 1, so that the keepers can be removed or replaced.

Thus it will be seen, that after the motor head has been removed, the device is placed on one of the head bolts with the recesses 4 fitting over the seats of the springs with the stems passing through the holes 2. Then the nut 12 is placed on the bolt and tightened to cause the member 1 to compress the springs and then the keepers can be removed by the fingers. After the keepers of one pair of valves are removed the device can be placed on another bolt and another pair of keepers removed.

With this invention the springs can be easily and quickly depressed to enable the keepers to be removed or replaced.

It is thought from the foregoing description that the advantages and novel features of the invention will be readily apparent.

It is to be understood that changes may be made in the construction, combination and arrangement of the several parts, provided such changes fall within the scope of the appended claim.

What we claim and desire to protect by Letters Patent is:

A valve spring compressor adapted for use on motors which have a pair of valves located adjacent a head stud bolt, said compressor comprising a piece of inflexible metal of substantially triangular configuration having a tubular part extending from one side thereof adjacent the apex of the triangle the bore of the tubular part being of such size as to closely embrace a head stud bolt and guide the compressor as it is actuated by a nut associated with the stud bolt and companion apertures formed therein adjacent the base of the triangle to receive the valve stems of a motor, each aperture merging into an enlarged countersunk recess on that side of the compressor carrying the tubular part to receive the ends of the springs to be compressed, and each aperture on the opposite side of the compressor merging into cup-shaped recesses in the opposite surface of the compressor to facilitate the removal of valve keepers.
